UNITED STATES PATENT OFFICE.

JOHN E. TYLER, OF ROXBEL, NORTH CAROLINA.

FENCE.

No. 853,846.

Specification of Letters Patent.

Patented May 14, 1907.

Application filed October 5, 1906. Serial No. 837,554.

To all whom it may concern:

Be it known that I, JOHN E. TYLER, a citizen of the United States, and a resident of Roxobel, in the county of Bertie and State of North Carolina, have invented certain new and useful Improvements in Fences, of which the following is a specification.

My invention is an improvement in fence posts; and consists in certain novel constructions and combinations of parts as will be hereinafter described and claimed.

In the drawing Figure 1 is a side view partly in section of a post embodying my invention. Fig. 2 is a face view thereof. Fig. 15 3 is a cross-section on about the line 3—3 of Fig. 1, and Fig. 4 shows a somewhat different construction from that shown in Figs. 1 and 2.

My invention relates particularly to posts having a concrete base and a wooden or similar standard.

The concrete base A shown in Figs. 1 and 2 may be of any suitable concrete material and be molded in the manner well known to those skilled in the art. It is provided at its lower end with an enlarged or foot portion A' but this may be omitted if desired as will be understood from Fig. 4. On one side the base A is provided at a suitable distance below its upper end with a lateral offset A², forming a shoulder A³ at its upper side on which rests the standard B, said standard being preferably composed of slats B' between which the wires C of the fence fabric are secured by means of bolts D which also operate to secure the standard to the concrete base, such bolts D passing through the standard and also through the upper wing A⁴ of the post, such wing A⁴ projecting above the shoulder A³ before described. By this construction the fence material is held firmly to the standard of the post, and the post standard is held to the base and I also provide means for securing the lower wire C' of the fence material in connection with the base. To this end I provide the base in the same side and below the shoulder A³ with a groove to receive the wire C' and with a securing device extending over the outer end of said groove to retain the wire C' in place.

50 In Fig. 4 the groove a is formed in the lower side of the offset portion A² and a bolt d extends through the concrete base across the groove a below the wire C' and thus operates to retain the said wire in the groove, the bolt d also extending through that por-

tion of the offset A² outside of the groove a as shown in said Fig. 4. This construction may be employed when desired but I prefer to employ the construction shown in Figs. 1 and 2 in which the groove a' is formed in the 60 upright face of the base and preferably in said face of the offset portion A² to receive the lower wire C' of the fence material as shown. This groove a' is curved from end to end to avoid deflecting to any greater extent 65 than necessary the lower wire of the fence material in order to prevent the breakage of the galvanizing thereon and also to increase the hold of the wire in the groove and the wire when fitted in this groove a' is held by a 70 cover plate E fitting against the face of the post over the outer side of the groove a' and secured by a crossbolt d' extending through the base A above the groove a', the cover plate being thus secured by the bolt d' and 75 projecting down over the groove a' to hold the wire in said groove in the operation of the invention as will be understood from Figs. 1 and 2.

The construction is simple, easily applied 80 and efficiently serves the purpose for which it is designed.

The concrete base may if desired be reinforced by wires F extending longitudinally within the post and disposed laterally, as 85 shown in Fig. 3, and having their ends coiled or deflected as will be understood from Fig. 1 of the drawing.

It will be noticed from the drawing that the wooden standard is held clear of the 90 ground by the base in order to retard decay and thus lengthen the life of the standard.

What I claim is—

1. The combination substantially as herein described, of the base having at one side 95 a lateral off-set forming an upwardly facing shoulder at its upper side, and provided in the face of said off-set with a groove curved from side to side, the standard composed of slats mounted upon the said off-set, bolts 100 securing said slats together and to the upwardly projecting portion of the base, the fence material having wires held between the said slats and having its bottom wire held in the curved groove in the face of the 105 off-set of the base, a cover plate projecting over said groove, and a bolt extending through said cover plate and base above the groove and securing the plate to the base, substantially as set forth.

2. The base having at one side a lateral off-set forming an upwardly facing shoulder and provided below the said shoulder with a groove to receive a fence wire combined with a standard mounted on said upwardly facing shoulder and secured to the base above the said shoulder, and the fence material secured to the said standard and having its bottom wire arranged in the groove in the base, and a securing device held to the base and projecting over the said groove to retain the wire therein, substantially as set forth.
3. The combination substantially as herein described, of a base having a lateral off-set forming an upwardly projecting shoulder, and provided below said shoulder with a groove curved from side to side, a cover plate projecting over said groove to retain a wire therein, a bolt passing transversely through the base and securing the cover plate thereto, and a standard mounted on the upwardly

facing shoulder and secured to the base, substantially as set forth.

4. A post having a concrete base and a standard secured thereto and provided in the concrete base below the standard with a groove extending from side to side and adapted to receive a fence wire, and means for retaining the fence wire in said groove, substantially as set forth. 25

5. A base having an off-set portion forming an upwardly facing shoulder to receive a standard, and provided in its off-set portion below said shoulder with a groove to receive a fence wire, and means for retaining the fence wire in said groove, substantially as set forth. 30 35

JOHN E. TYLER.
